CLAIM

The ornamental design for a modular connector wiring system, as shown and described.

DESCRIPTION

FIG. 1 is a top, front and right side perspective view of a modular connector wiring system showing our new design; FIG. 2 is a bottom, front and left side perspective view thereof;

FIG. 3 is a bottom, rear and left side perspective view thereof; FIG. 4 is a top plan view thereof;

FIG. 5 is a bottom plan thereof;

FIG. 6 is a right side elevation view thereof;

FIG. 7 is a left side elevational view thereof;

FIG. 8 is a front elevation view thereof; and,

FIG. 9 is a rear elevation view thereof.

The broken line depicts internal elements of the modular connector wiring system, shown in FIGS. 8 and 9, is unclaimed subject matter, and forms no part of the claimed design.
